(57) **CLAIM**

The ornamental design for a vehicle sign having base and flag, as shown and described.

DESCRIPTION

FIG. 1 is a perspective view of a vehicle sign having base and flag incorporating my design;

FIG. 2 is an enlarged perspective view of the flag of the vehicle sign of FIG. 1 incorporating my design removed from the base for clarity of disclosure;

FIG. 3 is a reduced scale front elevational view of the flag of FIG. 2;

FIG. 4 is a top plan view of the flag of FIG. 2;

FIG. 5 is a right side elevational view of the flag of FIG. 2;

FIG. 6 is a reduced scale rear elevational view of the flag of FIG. 2;

FIG. 7 is a bottom plan view of the flag of FIG. 2;

FIG. 8 is a left side elevational view of the flag of FIG. 2;

FIG. 9 is a perspective view of the base of the vehicle sign of FIG. 2 incorporating my design with the flag removed for clarity of disclosure;

FIG. 10 is a left side elevational view of the base of FIG. 9;

FIG. 11 is a top plan view of the base of FIG. 9;

FIG. 12 is a front elevational view of the base of FIG. 9;

FIG. 13 is a right side elevational view of the base of FIG. 9;

FIG. 14 is a bottom plan view of the base of FIG. 9; and,

FIG. 15 is a rear elevational view of the base of FIG. 9.
